UNITED STATES PATENT OFFICE.

ALFRED L. EUSTICE, OF CHICAGO, ILLINOIS.

FUSE-TERMINAL PACKING.

Original application filed March 31, 1919, Serial No. 286,446. Divided and this application filed August 9, 1919. Serial No. 316,415.

To all whom it may concern:

Be it known that I, ALFRED L. EUSTICE, a citizen of the United States, residing at Chicago, in the county of Cook and State 5 of Illinois, have invented certain new and useful Improvements in Fuse-Terminal Packings, of which the following is a specification.

This is a division of application Serial 10 No. 286,446, filed March 31st, 1919, in which is described and broadly claimed a fuse terminal attaching means comprising a disk attached to a terminal to provide a fixed 15 abutment thereon, and to serve as a means for centering the terminal in the shell; while an anchoring member overlying the end of the shell, held thereon by the cap or ferrule, and interlocking with the shell against rotation, carries a pair of locking members 20 which conform to the section of and embrace the terminal between the fixed abutment and shoulders thereof, but which is readily releasable therefrom to facilitate assembly of the connected fuse and terminal with the 25 shell; the fixed abutment in that instance also serving as a gas check on the under side of the anchoring member.

The present invention embodies the features above described, but provides means 30 for making a more effective gas check, and to this end a movable packing disk is located between the fixed abutment and the anchoring member, fits snugly around the terminal, and is pressed by a spring against the under 35 side of the anchoring member in a manner to check the escape of gas past the latter; the preferred construction of this organization of elements being made to embody the additional features of having the locking 40 members of the anchoring member intersected with the terminal so as to find their fixed abutments thereon, and having the packing disk spring intersect the terminal in a diametric position relatively to the 45 packing disk.

The present invention will be fully understood upon reference to the accompanying drawing, in which—

Figures 1 and 2 are axial sectional views 50 in planes at right angles to each other, showing the preferred construction of a fuse embodying the features of the present invention.

Figure 3 is a section on the line 3^x—3^x of 55 Figure 1, and

Figures 4 and 5 are, respectively, an under face view and an edge view of the anchoring disk with its locking members in releasing position.

1 represents a shell, which is preferably bushed at its ends by metal liners 2, threaded into the shell at 2^a and having external threads 2^b that receive the securing ferrules 3. 4 represents the terminal, which in the present illustrative embodiment is a so-called knife blade terminal; but it is to be understood that, as a securing and gas check means, the features of the present invention will be applicable to a terminal which serves only to hold the fusible link within the shell, and to electrically connect the same with the ferrule 3, if it should be desired to use the latter as the means of electrically introducing the fuse into the circuit. Terminal 4 carries a fixed abutment 5, which is preferably in the form of a circular disk which may be made to substantially fit within the bushing 2 and thereby center the terminal and its fusible link within the shell. The fixed abutment is preferably secured 80 permanently to the terminal 4, as, for instance, by striking up the metal, as indicated at 5^x.

The means for holding the terminal against longitudinal and rotary motion on 85 the shell comprises an anchoring disk 6 slotted to fit the section of the terminal 4, and of such diameter that it will fit over the end of the shell and be clamped thereon by the ferrule 3, and which carries lugs or 90 projections 7 that enter notches 8 in the liner of the shell, so that when it is so clamped in position, it will be adapted to hold the terminal against rotation in addition to holding it longitudinally.

The anchoring member 6 is further provided with means for releasably interlocking it with the terminal 4, which interlocking means preferably also serves to render the anchoring means, in its relation to the terminal and fixed abutment, sufficiently 100 gas-tight to prevent longitudinal discharge of gas incident to blowing of the fuse.

The interlocking means carried by the disk 6 is in the form of a divided disk, the 105 members 9 of which, pivoted upon the pintles 7, are recessed on their meeting edges to conform to the reduced section 5^a of the terminal blade 4, and also to provide tongues 9^{ax} that meet within a slot 4^b of the terminal 110

4. By this means the anchoring member finds its inner fixed abutment by direct engagement with the terminal, and to that extent is somewhat similar in principle to 5 the construction shown in application Serial No. 241,115; and the outer lamina 5^{ax} of the fixed abutment disk 5, in order that it may serve as a gas check, fits snugly around the blade 4 and is pressed against the locking 10 member 9^a by means of a spring 11 introduced between it and the fixed locking disk. Both the inner fixed member 5 and the packing disk 5^{ax} assume the relation of a means for centering the terminal in the shell. The 15 projections 7 drop into recesses in the end of the shell to hold the anchoring member 6 against rotation, and the member 6, being firmly gripped upon the terminal 4, is adapted to hold the latter against rotation; 20 and when the anchoring member is clamped upon the end of the shell, it is adapted to hold the parts against longitudinal displacement.

It will be seen that the internal flange of 25 the ferrule 3 overlaps the anchoring member 6 so as to effectively check the escape of gas around the outer edge of the anchoring member, to compel the gas to escape by way of the circuitous passage afforded by the 30 threads.

It is to be noted that the fixed abutment 35 5 provides a limiting stop for the inward movement of the gas check 5^{ax}, and that this fixed abutment, being located in close proximity to the bearing of the spring 11, also sustains the latter against bending inward beyond its elastic limit when the gas check is depressed to admit the interlocking members 9^a to the reduced section 5^a of the 40 terminal.

I claim:

1. In a fuse, a shell, a terminal entering 45 said shell, an anchoring member engaging the terminal to resist both longitudinal and rotary movement thereof, and a packing disk mounted upon the terminal on the inner side of the anchoring member and having means for pressing it against the latter to check the flow of gas longitudinally past 50 the same.

2. In a fuse, a shell, a terminal entering 55 said shell, an anchoring member engaging the terminal to resist both longitudinal and rotary movement thereof, a packing disk movably mounted upon the terminal within the shell, and a spring pressing said packing disk against the inner face of the anchoring member.

3. In a fuse, a shell, a terminal entering 60 said shell, an anchoring member engaging the terminal to resist both longitudinal

and rotary movement thereof, a packing disk movably mounted upon the terminal within the shell, and a spring pressing said packing disk against the inner face of the anchoring member; said spring being supported by the terminal.

4. In a fuse, a shell, a terminal entering 70 said shell, an anchoring member engaging the terminal to resist both longitudinal and rotary movement thereof, a packing disk movably mounted upon the terminal within the shell, and a spring pressing said packing disk against the inner face of the anchoring member; said spring being extended through the terminal in diametric relation to the packing disk.

5. In a fuse, a shell, a terminal entering 80 said shell, an anchoring member engaging the terminal to resist both longitudinal and rotary movement thereof, a packing disk movably mounted upon the terminal within the shell, and a spring pressing said packing disk against the inner face of the anchoring member; said packing disk being adapted 85 to center the terminal in the shell.

6. In a fuse, a shell, a terminal entering 90 said shell, an anchoring member engaging the terminal to resist both longitudinal and rotary movement thereof, a packing disk movably mounted upon the terminal within the shell, a spring pressing said packing disk against the inner face of the anchoring member, and a fixed abutment disk mounted on the terminal on the opposite side of 95 the spring from the packing disk.

7. In a fuse, a shell, a terminal entering 100 said shell, an anchoring member engaging the terminal to resist both longitudinal and rotary movement thereof, a packing disk movably mounted upon the terminal within the shell, a spring pressing said packing disk against the inner face of the anchoring member, and a fixed abutment disk mounted on the terminal on the opposite side of 105 the spring from the packing disk; said fixed abutment disk being adapted to center the terminal in the shell.

8. In a fuse, a shell, a terminal entering 110 said shell, an anchoring member interlocked with the terminal against both longitudinal and rotary movement, means securing the anchoring member upon the end of the shell, and a packing disk having means for pressing it against the inner face of the anchoring 115 member; the fixing of said anchoring member relatively to the terminal in the longitudinal direction being independent of the packing disk.

Signed at Chicago, Illinois, this 30th day 120 of July, 1919.

ALFRED L. EUSTICE.
